UNITED STATES PATENT OFFICE.

HARRY E. THOMPSON AND PERCY L. BUNN, OF THREE RIVERS, MICHIGAN,
ASSIGNORS, BY MESNE ASSIGNMENTS, TO FAIRBANKS, MORSE & CO., OF
CHICAGO, ILLINOIS, A CORPORATION OF ILLINOIS.

STANDPIPE.

1,342,516.

Specification of Letters Patent.

Patented June 8, 1920.

Application filed September 19, 1918. Serial No. 254,744.

To all whom it may concern:

Be it known that we, HARRY E. THOMPSON and PERCY L. BUNN, citizens of the United States, residing at Three Rivers, county of St. Joseph, State of Michigan, have invented certain new and useful Improvements in Standpipes, of which the following is a specification.

This invention relates to improvements in standpipes.

The main objects of this invention are:

First, to provide an improved standpipe or water column which is very easily and quickly adjusted to deliver to tanks of varying heights.

Second, to provide an improved standpipe or water column which is quite simple and economical in structure and at the same time one which is very durable and not likely to get out of repair or become inoperative in use.

Further objects, and objects relating to structural details, will definitely appear from the detailed description to follow.

We accomplish the objects of our invention by the devices and means described in the following specification. The invention is clearly defined and pointed out in the claims.

A structure which is a preferred embodiment of our invention is clearly illustrated in the accompanying drawing, forming a part of this specification, in which:

Figure I is a detail side elevation of our improved standpipe or water column.

Fig. II is a detail rear elevation.

Fig. III is a vertical section through the discharge nozzle showing the arrangement of the discharge spout on the nozzle.

Fig. IV is a detail section on a line corresponding to line 4—4 of Fig. II, showing the arrangement of the counterweight supporting cables.

Fig. V is a detail transverse section on a line corresponding to line 5—5 of Fig. I.

In the drawing similar reference characters refer to similar parts throughout the several views, and the sectional views are taken looking in the direction of the little arrows at the ends of the section lines.

Referring to the drawing, 1 represents the vertical portion of the standpipe which is provided at its upper end with a laterally projecting discharge nozzle 2. The delivery

or discharge spout 3 is telescopically arranged over the discharge nozzle, being provided with a roller 4 or other part traveling or riding upon the top of the discharge nozzle so that the discharge spout is supported for longitudinal and vertical adjustment.

The inner end of the spout is of such dimensions relative to the nozzle as to allow some movement laterally as well as the longitudinal and vertical movements. The spout is supported by a lever 5 pivotally mounted at 6 on the bracket 7 projecting upwardly above the nozzle. At its front end the lever is provided with a cross arm 8.

The spout 3 is provided with a stirrup 9 to which the suspending cables 10 secured to the ends of the cross arm 8 are connected, so that the cables embrace the spout and being secured at the sides thereof support the same against rotative movement, and also the cables thus connected accommodate the arm 11 between them, which arm is provided to support the valve and other operating mechanisms of the standpipe, such operating mechanisms, however, not being shown as they form no part of this invention.

At its rear end the lever is provided with segments 12 carried by the arm 19 of the lever and is also provided with auxiliary counterweights 14, which are, in the structure illustrated, parts of the segments.

The suspending cables 15 for the main counterweights 16 are arranged over these segments so that as the lever is swung the cables remain in substantially the same vertical plane.

The counterweights 16 are preferably made up of a series of blocks as illustrated. The discharge spout 3 is preferably provided with a handpiece 17 at its outer end so that it may be conveniently manipulated from the tender. A chain 18 limits the outward movement of the spout.

With this arrangement of parts the spout may be conveniently manipulated to raise and lower it to position and has the further advantage of being very simple in structure and economical and durable in use.

We have illustrated and described one embodiment of our invention. We have not attempted to illustrate or describe other embodiments which we contemplate as we believe the disclosure made will enable those skilled in the art to which our invention re-

lates to embody or adapt the same as may be desired.

Having thus described our invention, what we claim as new and desire to secure 5 by Letters Patent, is:

1. In a water column or standpipe, the combination of a vertical pipe, a laterally projecting discharge nozzle therefor, a discharge spout telescopically arranged over 10 said discharge nozzle for longitudinal and pivotal adjustment thereon, a bracket projecting above said nozzle, a lever provided with a cross arm at its front end pivotally mounted on said bracket projecting over 15 said discharge spout, a stirrup on said discharge spout disposed in front of its center of gravity, suspending cables connected to said stirrup at the sides of said spout and to the ends of said lever cross arm, counter- 20 weights, suspending cables therefor connected to the rear end of said lever, and segments on the rear end of said lever over which said suspending cables are arranged so that as the lever is actuated the cables re- 25 main substantially in the same vertical plane.
2. In a water column or standpipe, the combination of a vertical pipe, a laterally projecting discharge nozzle therefor, a discharge spout telescopically arranged over 30 said discharge nozzle with its rear end riding on the top thereof and for longitudinal and pivotal adjustment thereon, a bracket projecting above said nozzle, a lever pro- 35 vided with a cross arm at its front end pivotally mounted on said bracket projecting over said discharge spout, a stirrup on said discharge spout disposed in front of its center of gravity, and suspending cables 40 connected to said stirrup at the sides of said spout and to the ends of said lever cross arm.
3. In a water column or standpipe, the combination of a vertical pipe, a laterally projecting discharge nozzle therefor, a discharge spout arranged over said discharge 45 nozzle and having a roller at its rear end traveling on the top of the nozzle whereby the spout is supported for longitudinal and swinging adjustment, a lever projecting over 50 said discharge spout and provided with a cross arm, a pair of spout supporting cables connected at the sides of said spout and to the ends of the cross arm of said lever, and a counterweight connected to the rear end 55 of said lever.
4. In a water column or standpipe, the combination of a vertical pipe, a laterally projecting discharge nozzle therefor, a discharge spout arranged over said discharge 60 nozzle with its rear end riding on the top thereof and for vertical and longitudinal adjustment, a pivotally mounted lever project- 65 ing over said discharge spout and provided with a cross arm, and a pair of spout sup- porting cables connected at the sides of said

spout and to the ends of the cross arm of said lever.

5. In a water column or standpipe, the combination of a vertical pipe, a laterally projecting discharge nozzle therefor, a discharge spout telescopically arranged over 70 said discharge nozzle with its rear end recipro- cally supported thereon, a bracket projecting above said nozzle, a lever pivotally mounted on said bracket projecting over 75 said discharge spout, a spout suspending cable connected to said lever, a counter- weight, a suspending cable therefor connected to the rear end of said lever, and a segment on the rear end of said lever over 80 which said suspending cable is arranged so that as the lever is actuated the cable re- mains substantially in the same vertical plane.

6. In a water column or standpipe, the combination of a vertical pipe, a laterally projecting discharge nozzle therefor, a discharge spout telescopically arranged over 85 said discharge nozzle and provided with a roller at its rear end traveling on said nozzle, a lever projecting over said discharge spout, and a spout suspending cable for said spout connected to said lever.

7. A water column or standpipe provided 90 with a discharge nozzle, a discharge spout operatively associated with said nozzle, a lever projecting over said discharge spout, a cable connecting said discharge spout and lever, a counterweight, a suspending cable therefor, and a segment on said lever over 95 which said suspending cable is arranged so that as the lever is actuated the cable re- mains substantially in the same vertical plane.

8. In a water column or standpipe, the combination of a vertical pipe, a laterally projecting discharge nozzle therefor, a discharge spout arranged over said discharge 100 nozzle and having a part at its rear end traveling on the top of the nozzle whereby the spout is supported for longitudinal and swinging adjustment, a lever projecting over 110 said discharge spout, a spout supporting cable connected to said lever, and a counterweight connected to the rear end of 115 said lever.

9. In a water column or standpipe, the combination of a vertical pipe, a laterally projecting discharge nozzle therefor, a telescoping discharge spout arranged over 120 said discharge nozzle with its rear end adapted to slide along the top thereof, a supporting lever fulcrumed above and project- 125 ing over said discharge spout, and a spout supporting cable carried by said lever connected to said discharge spout in front of its longitudinal center of gravity.

10. In a water column, or standpipe, the combination of a vertical pipe, a laterally projecting discharge nozzle therefor, a dis- 130

charge spout arranged over said discharge nozzle for vertical and longitudinal adjustment thereon, a supporting lever fulcrumed above and projecting over said discharge spout, and a spout supporting cable carried by said lever connected to said spout in front of its longitudinal center of gravity.

11. In a water column or standpipe, the combination of a vertical pipe, a laterally projecting nozzle therefor, a discharge spout arranged over said discharge nozzle for pivotal and longitudinal adjustment thereon, a lever pivotally mounted to project over said

discharge spout, a spout supporting cable connected to the front end, and a counter-balance connected to said lever at the rear of its pivot.

In witness whereof we have hereunto set our hands and seals in the presence of two witnesses.
